UNITED STATES PATENT OFFICE

WARD LEATHERS, OF HAWORTH, NEW JERSEY, ASSIGNOR TO THE QUADREX CORPORATION, A CORPORATION OF CONNECTICUT

DOUBLE FILTER FOR VACUUM CLEANERS

Application filed December 12, 1930. Serial No. 501,877.

The object of my invention is to produce a simple filter for vacuum-cleaners of high efficiency for its size and bulk.

In order to accomplish this purpose in the simplest manner, I have invented a filter which consists of a double fabric duct surrounding the handle of the vacuum-cleaner and have so devised it that it may be simply made and assembled, and at the same time with the full outside area of both ducts for air filtering purposes.

In order to set forth my invention in such terms that all may understand it, I have prepared the following specification and attached drawing of which—

Figure I is a partially sectioned lateral view of a vacuum-cleaner with filter.

Figure II is a cross-section of the double duct filter.

Figure III is a detail of the filter cloth.

Figure IV shows the filter applied to conventional cleaners.

In Figure I, 1 is a vacuum-cleaner nozzle made integral with the motor-blower housing 2 and supplied with a lifting roller 3 for lightening the weight on the floor. The dotted line 4 indicates the motor-housing which is surrounded by a casing 5, for deflecting the dirt-laden air upward. The filter 6 made of any suitable fabric, or other filter material, is disposed about a rigid handle 7 which may be supported at its bottom end by the motor-housing 4, if desired. The filter 6 is made of an upper and a lower duct, the upper duct for the upward movement of the dirt-laden air, and the lower duct for the downward movement of the dirt-laden air until the dirt

is deposited in a suitable receptacle 8. The outer covering of the upward end of the filter 6 may be provided with a series of gores 9, and the fabric itself, gathered about the handle 7 at 10 and suitably attached thereto.

Such attachment may very simply consist of tying, then covering with a metal ferrule. On both sides of the filter are grommets or eyelets, 11, for permitting the exhaust of filtered air from the inner walls of both upper and lower air filter ducts. The lower end of

the filter by spreading slightly at 12', becomes two chambers, completely surrounded by fabric, each of which may be joined in suitable manner to the supporting cross-member (see Figure IV).

Figure II shows a cross-section of the filter taken in any typical location and showing the inner structure of the filter itself. A single piece of fabric forms a cylindrical filter sleeve 6. Two other pieces of fabric 12 and 13 are joined to the sleeve 6 and extend across its diameter, approximately as indicated. The part 12 is sewn to the part 6 at 14 and 15. The part 13 is sewn to the part 6 at 16 and at 17, where 13 and both sides of 11 may be joined by a single seam 17. The filter is now divided by the fabric partitions 12 and 13 into three chambers, 18 and 19 for dirt-laden air and 20 for clean air. If the filter, as illustrated, is turned inside out through the chamber 20, the seam at 17 will be on the inside. Before the seam is made, rows of grommets at 11 are put in place and if the filter is to be turned, the finished sides are naturally first placed on the inside. The seams at 14, 15, and 16, may be turned as shown, or the edges may be in the chamber 20, and caught within the grommets. To get them, with 17 inside, it will be necessary to turn the filter twice, namely, first through the chamber 18 and then through the chamber 20. The handle 7 is shown surrounded by a corrugated screen 22, which maintains an air breathing space about the handle, permitting the use of the entire areas of the parts 12 and 13 for filter purposes.

Figure III shows, in the diagram, the upper end of the part 12 (and 13). The seams 14 and 15 join the part 12 to the part 6, but at a reasonable distance from the top, 90 these seams are discontinued, and the seams 23 and 24 are used to join the part 12 to the part 13. The area shown at 25 is therefore half of a small sleeve which neatly surrounds the handle 7. When the areas 26 and 27 are 95 cut away, it is obvious that the chamber 18 is joined at the top of the filter to the chamber 19 (compare Fig. IIa), in such manner that there can be no other air leakage from the dirt-laden chambers than that permitted 100

by the filter material itself, for the sleeve 25 is tied underneath the gathered end of 6 at 10 in Figure I.

In Figure IV, I have shown my double 5 chamber filter applied to a conventional vacuum cleaner where the dirt-laden air is carried upward from the motor-blower through the hollow yoke 28 and a tube 29 to a supporting cross member 30 which 10 supports the handle 7. At 30 reasonably air-tight junctures are made between the duct 29 and the chamber 18, and between the chamber 19 and the dirt receptacle 8. The dirt receptacle is held in place by any suitable clamp, or latches, easily provided. 15

It is now evident that the flow of dirt-laden air throughout the first half of the filter process is upward toward the top, and it is equally evident that the air movement 20 through the filter at the point where it is reversed from an upward to a downward flow is approximately half its entrance speed and volume. Since this flow is sufficient to carry the dirt into the duct 19, and since half of the 25 air filtration is accomplished at such time as the air movement is approximately toward gravity, the dirt will be deposited in the receptacle 8. It is further evident that the filtered air escaping through the filter parts 30 12 and 13 will be discharged through the grommets shown.

Having set forth my invention in terms so clear that all those familiar with these arts may readily understand, I wish it further understood that these principles may be applied in various and devious forms of design without departing from the spirit of my invention.

I claim:

40 1. In a vacuum-cleaner, in combination, a motor-blower, a handle with no functional air passage therein, said handle surrounded by a filter sleeve, with two porous partitions in said filter sleeve joined to the sides 45 thereof, dividing it into three chambers with the handle passing through the middle chamber, the outer chambers communicating at the top of said filter, air-discharge openings along the side of the middle chamber, 50 and a dirt receptacle in communication with one of the outer chambers at the lower end thereof.

2. In a vacuum-cleaner, in combination, 55 a motor-blower, a dirt receptacle, a handle with no functional air passage therein, said handle disposed between two dirt-laden air porous walled chambers in a manner to maintain an air discharge space between them, said dirt-laden air chambers joined along their outer sides and communicating at the top, air-discharge ports along said joined sides and communicating with the handle chamber, and one of said 60 dirt-laden air chambers being in communica- 65

tion at its bottom end with the dirt receptacle. Signed at New York, in the county of New York and State of New York, this eleventh day of December, A. D. 1930.
